CARBURETOR

Frank D. Warburton, Southgate, Calif.

Application June 10, 1944, Serial No. 539,633

7 Claims. (Cl. 261—41)

1

This invention has to do with carburetors. It is among the principal objects of my invention to provide a carburetor of extremely simple and efficient construction; which eliminates the necessity of the bothersome adjustments found necessary in conventional carburetors; which requires no float; which provides maximum air velocity in the mixing chamber; and which effects highly efficient fuel atomization.

The invention has still further features of novelty and advantage which will become obvious from the following description wherein, for purposes of explaining my invention, I describe in detail one presently preferred embodiment thereof. I wish it understood at the outset, however, that the invention, in its broader aspects as defined by the accompanying claims, is not intended to be limited to the details of structure and association of parts now to be specifically set forth, since it is capable of being carried out in other physical forms which the ensuing explanation will suggest to those working in this art.

In the following description I shall refer to the accompanying drawings, in which:

Fig. 1 is a medial vertical section;

Fig. 2 is a top plan view;

Fig. 3 is a cross section on line 3—3 of Fig. 1; and

Fig. 4 is a fragmentary side elevation.

In the drawings I show my carburetor as comprising a body 5 adapted to be secured on the intake manifold 6 of an internal combustion engine by bolts 7.

The body is provided with a longitudinal passageway 10 defining a Venturi throat 11, and a mixing chamber 12, the intake end of the passageway being controlled by a butterfly valve 15 which is mounted in a transverse slot 16 in an operating shaft 17 journalled at its ends in the side wall of the body, the butterfly being secured in the slot by set screws 18.

A sleeve valve 20 is rotatably mounted axially of the body, its top end being provided with a ring 21. The sleeve has a plurality of main outlet ports 22 which are adapted to be moved into and out of register with a well 24 from which a main fuel passageway 23 in the body leads to communicate with a main fuel discharge passageway 25 disposed longitudinally in the body,

2

the outlet end of the latter passageway having a jet member 26 threaded therein. Thus the charge of fuel admitted to well 24 and from there to passageway 25 depends upon the number of sleeve ports 22 which may be in register with the well at any given time. I show one of the ports 22 in register with the well, but a further counterclockwise rotation of the sleeve will move one or more additional ports 22 into register with the well and thus increase the supply of fuel charge.

Sleeve 20 also has an outlet port 30 adapted to be moved into and out of register with an outlet passageway 31 in the body to supply fuel, for motor idling, through a longitudinal passageway 32 which has a jet 34 screwed into its discharge end. The idling fuel flow through passageway 32 may be adjusted by the needle valve 35 which is threaded into a hole 35a in the body, the hole intersecting passageway 32.

The approximately 45° angular disposition of the jets 36, 34 in the Venturi throat causes the fuel discharged therefrom to be more effectively broken up. In practice I find that the fuel becomes initially deposited in highly atomized condition around the side wall of the mixing chamber and on the butterfly valve 15 so that its admixture with the incoming air stream is greatly facilitated.

30 A cap 40 has its inwardly disposed flanged portion 41 threaded on to the body and its top wall 42 bears against the sleeve 20 sufficiently to maintain a relatively tight seal. The purpose of the cap 40 is to provide an annular fuel chamber 45 into which fuel is delivered through line 46 from the fuel source.

40 A neoprene seal ring 50 seats around the sleeve 20 and against the inner surface of the top wall 42 of the cap and a compression spring 51 bears at one end against the ring and at its other end against the lower flanged portion of the sleeve, so that not only is the sleeve ring constantly urged into sealing relationship with the end wall 42, but also the flanged portion of the sleeve is urged against the tapered body surface against which it rotates, to prevent leakage. A seal ring 52 is provided between the lower end of cap 40 and the body.

45 On an outer end of the shaft 17 I secure an operating arm 54 for the butterfly valve which

may be connected by linkage 55 with the accelerator throttle conveniently provided in the driver's compartment of a vehicle. The arm is provided with a cam portion 56 which engages a radial follower pin 57 carried by the ring 21, so that the sleeve valve 20 may be operated in unison with the butterfly valve 15. To rotate the sleeve 20 in the opposite direction as the arm 54 is swung back, I utilize a coil spring 58 which is secured at one end to the ring 21 as by a screw 58a and secured to the cap wall 42 by a screw 58b.

While any desired number of ports 22 may be provided I prefer to utilize and show three such ports. The ports 22, 23 and 30, 31 are so relatively disposed that the idling port 31 is closed when one or more of the ports are in register with well 24, and vice versa.

From the foregoing it will be observed that when the butterfly valve 15 and sleeve 20 are simultaneously operated for operation of the motor, the air entering the inlet end of the passageway 10 past the butterfly draws fuel from the jet 26, the fuel also being under pressure in chamber 45 by virtue of action of the conventional fuel pump in the fuel line, not shown. The velocity of the explosive charge is thus maintained at its maximum since there is no intervening gate or butterfly valve between the mixing chamber and the intake manifold, as is the case in conventional carburetors.

I claim:

1. A carburetor comprising a body presenting an air passageway therethrough, a control valve operably associated with the passageway, actuating means associated with the control valve, walls providing a fuel supply chamber annularly of the body, a fuel port in the body communicating at its inlet end with the chamber and at its discharge end with the passageway, and a sleeve valve rotatably mounted on the body within the chamber for cooperation with the inlet end of the fuel port, said sleeve valve being operable in response to said actuating means to establish variable communication between the fuel supply chamber and said fuel port.

2. A carburetor comprising a body having a longitudinal passageway therethrough providing a Venturi throat, a control valve in the inlet end of the passageway, wall means providing a fuel chamber annularly of the body, the body having a fuel port, said port communicating at its inlet end with the fuel supply chamber and communicating at its outlet end with the passageway adjacent the throat, a sleeve valve rotatably mounted on the body within the chamber in position to open and close the inlet end of said port, means for actuating the control valve, and means for rotating the sleeve valve.

3. A carburetor comprising a body of rounded cross section having a longitudinal passageway therethrough, said body being adapted to be mounted on the intake manifold of an internal combustion engine with said passageway in communication therewith, said passageway being of relatively increased diameter at and adjacent its inlet end which increased diameter portion intersects the adjacent portion in a beveled shoulder providing a Venturi throat, a butterfly valve swingably mounted in the intake end of the passageway in position spaced towards the inlet end from said throat, a sleeve-like cap secured on the body and providing therewith an annular fuel chamber, the body having a fuel port, said port communicating at its inlet end with the fuel

chamber and angularly communicating with the passageway through said beveled shoulder, and a sleeve valve mounted within the cap for rotation about the body in position to open and close the inlet of the port.

4. In a carburetor having a body presenting an air passageway therethrough and a valve controlling the inlet end of the passageway, means for controllably supplying fuel to said passageway, comprising walls providing an annular fuel chamber in the body, a fuel delivery port having a fuel-receiving well at its inlet end communicating with the chamber and having its discharge end communicating with the passageway, and a sleeve valve controlling passage of fuel from the chamber to said well, said sleeve valve being rotatably carried by the body.

5. A carburetor comprising a body presenting an air passageway therethrough, a butterfly valve swingably carried by the body in position to control the inlet end of the passageway, said body being adapted to be mounted on the intake manifold of an internal combustion engine with the discharge end of the passageway communicating therewith, means providing a Venturi throat in the passageway, wall means providing an annular fuel chamber in the body, the wall portion providing the bottom of said chamber being beveled, the body having a fuel supply port whose inlet end communicates with the fuel chamber through said beveled wall and whose outlet end communicates with the passageway, a sleeve valve rotatably carried by the body, said sleeve valve having a flanged portion disposed against said beveled wall portion, said flanged portion presenting an opening adapted to be moved into and out of registry with said port by virtue of rotation of the sleeve valve relative to the body, and spring means urging said flanged portion axially into engagement with said tapered wall portion.

6. A carburetor comprising a body presenting an air passageway therethrough, a butterfly valve swingably carried by the body in position to control the inlet end of the passageway, said body being adapted to be mounted on the intake manifold of an internal combustion engine with its discharge end communicating therewith, means providing a Venturi throat in the passageway, wall means providing an annular fuel chamber in the body, the wall portion providing the bottom of said chamber being beveled, a main fuel supply port in the body, an idling fuel supply port in the body, said respective ports having their inlets communicating with the chamber through said beveled wall portion and having their outlets communicating with the air passageway, a sleeve valve rotatably carried by the body, said sleeve having an annular flange disposed against said beveled wall portion, a pair of openings through said flange in position to alternately register with said ports in response to rotation of the sleeve valve relative to the body, and means urging said flange axially into engagement with said tapered wall.

7. A carburetor comprising a body presenting an air passageway therethrough, a control valve operatively associated with the inlet end of the passageway, walls providing a fuel supply chamber annularly of the body, one of said walls providing a well opening into the chamber, said body having a fuel port communicating at its inlet end with the well and communicating at its outlet end with the passageway, and a sleeve rotatably mounted axially of the body in position normally covering said well, and presenting a plurality of circumferentially spaced ports whose inlet ends

communicate with the fuel supply chamber, the outlet ends of said ports being normally out of register with the well but being adapted to be moved into register therewith by virtue of rotation of the sleeve.
